HOLDER FOR KEYS AND THE LIKE

Willard A. Ormsbee, Raynham, Mass., assignor to
 Taunton Pearl Works, Taunton, Mass., a corpora-
 tion

Application December 6, 1947, Serial No. 790,065

3 Claims. (CL. 70—459)

1

This invention relates to a holder for keys and the like.

My principal objects are to provide a holder with mechanism that will readily and smoothly slide from closed to open position and vice versa and, with the same mechanism, provide two compartments for keys or other articles either of which can be opened or closed by a simple, instantaneous operation. Another object is to so construct it that its utility is apparent at first glance.

Further objects are to construct said key holder so simply that it can be produced in large quantities at low cost, yet will be durable in use.

The foregoing and other objects which will appear as the nature of the invention is better understood, may be accomplished by a construction, combination and operative arrangement of parts such as is disclosed by the drawings and specification. The nature of the invention is such as to render it susceptible to various changes and modifications, and, therefore, I am not to be limited to said disclosure; but am entitled to all such changes therefrom as fall within the scope of my claims.

In the drawings;

Figure 1 is a perspective view of my key holder in locked or closed position, while Figure 2 is a similar view in unlocked or open position.

Figure 3 is a front elevational view of my key holder in locked position, the broken line showing the position of the slider when in open position.

Figure 4 is a front elevational view of my key holder in open position.

Figure 5 is a side elevational view of my key holder in normal or locked position.

Figures 6 and 7 are sectional views taken on the lines 6—6 and 7—7 of Figures 3 and 4 respectively.

Figure 8 is an enlarged, sectional view taken on the line 8—8 of Figure 5.

Figure 9 is a perspective view of the latch.

As illustrated, my holder has a bail or loop 10 having two sides, a supporting bar portion 10a at the bottom as shown, and an opening 12 at the top where the ends 11 of said bail are spaced apart. It is preferably made of a continuous piece of metal bent to any desired shape.

Said bail 10 is divided into two key holding compartments 13 by a slider 14 which has a post 16 that extends from above the top continuously to below the bottom of the holder thus dividing the bail into two compartments preferably equal in size. The upper portion of said post 16 is hollow, thus providing an opening for a latch,

2

later described. Said post upper portion terminates where a seat 17 is provided, below which is a lower portion that preferably is solid and of smaller diameter than the upper portion. A hole 18 extends laterally through said post at its lower end.

Holes 20 extend laterally through the hollow upper portion of said post 16 near the top, while other holes 21 extend laterally about midway through said hollow upper portion.

A coil spring 22 rests on said seat portion 17 and extends upwardly into said hollow portion of said post 16.

A latch member 25, forming part of said slider 14, movably extends into the hollow upper portion of said post 16 with its head 26 normally above said post 16 and its lower end resting on said coil spring 22. Said latch member 25 preferably has indents or sockets 28 in its upper portion to receive the ends of a hanger or end link 30 which extends through said holes 20 into said indents to keep said latch member 25 movably attached to said slider 14. There are also indents 32 in the lower portion of said latch member 25 and spaced angularly and below said indents 28, and a hole 34 extends laterally through said lower portion from one said indent 32 to the other.

The free ends 11 of said bail 10 extend normally through said holes 21 and a short distance into the lower portions of said indents 32. Normal position is illustrated in Figures 3 and 6 of the drawings.

A sleeve 36 preferably fits into and slidably extends through said hole 18 in said post 16 and said supporting portion 10a of said bail 10 extends through said sleeve 36 thus permitting smooth sliding action of said slider 14. Said bail 10 is bent to final shape after it is inserted 40 through said sleeve 36.

To insert keys or other articles into either of said compartments 13 said latch head 26 is depressed thus forcing said latch 25 downwardly which compresses said spring 22. Since said hole 45 34 in said latch 25 is normally above the free ends 11 of said bail and said holes 21 said bail cannot move laterally until said latch hole 34 is opposite said free ends 11. In the latter position, shown in said Figure 7, said slider 14 may be 50 wholly on either free end 11 to thus open whichever compartment 13 is desired, as illustrated in said Figures 2 and 4. After a key is inserted or removed from a said compartment said slider 14 is slid back to normal or center position, as 55 shown in Figures 3 and 6, whereupon said spring

22 automatically forces said latch 25 upwardly thus bringing said hole 34 above said free ends 11. In this position my holder is locked.

What I claim is:

1. A key holder comprising a single bail having two free ends extending towards each other and spaced apart, a slider slidably mounted on said free ends having an opening extending from the top inwardly and having holes therein at opposite sides and communicating with said opening and having other holes therein at opposite sides spaced angularly and longitudinally from the first said holes, a spring in said opening seated within said slider, said free ends extending into said first holes, a latch extending into said opening and abutting said spring and having two indents therein in side portions thereof and a hole extending from one said indent to the other and also having two other indents in side portions thereof spaced longitudinally from the first said indents and positioned opposite said slider other holes, and a hanger member extending into said slider other holes and into said other indents said latch indents being of such length to allow the latch to be moved to bring the hole therein in or out of registration with the first mentioned holes in the slider. 25

2. A key holder comprising a single bail having two free ends extending towards each other and spaced apart, a slider slidably mounted on said free ends having an opening extending from the top inwardly and having holes therein at opposite sides and communicating with said opening and having other holes therein at opposite sides spaced angularly and longitudinally from the first said holes, a spring in said opening seated within said slider said free ends extending into said first holes, a latch extending into said opening and abutting said spring and having two indents therein in side portions thereof and a hole extending from one indent to the other and also having two other indents in side portions there- 30

35 of spaced longitudinally from the first said indents and opposite said slider other holes, and a hanger member extending into said slider other holes and into said other indents said latch indents being of such length to allow the latch to be moved to bring the hole therein in or out of registration with the first mentioned holes in the slider.

40 3. A holder of the class described comprising a single bail embodying a lower supporting portion, an upper portion embodying two free ends spaced laterally apart and two side portions extending and flaring outwardly between said upper portion and said lower supporting portion, 15 a sleeve slidably mounted on said lower supporting portion, a slider post slidable on said free ends and mounted on said sleeve, said slider post having a laterally extending hole intermediate the ends thereof through which said sleeve laterally passes and extends laterally beyond said hole at opposite sides of said post, the lower half of said post being solid, each said free end being of sufficient length to independently receive said post in its full width.
